UNITED STATES PATENT OFFICE.

JOHN H. REDFIELD AND SAMUEL H. REDFIELD, OF LINKVILLE, OREGON.

BREECH-LOADING FIRE-ARM.

SPECIFICATION forming part of Letters Patent No. 403,959, dated May 28, 1889.

Application filed October 2, 1888. Serial No. 287,002. (No model.)

To all whom it may concern:

Be it known that we, JOHN H. REDFIELD and SAMUEL H. REDFIELD, citizens of the United States, residing at Linkville, in the 5 county of Klamath and State of Oregon, have invented a new and useful Improvement in Breech-Loading Guns, of which the following is a specification.

Our invention relates to an improvement in 10 breech-loading guns; and it consists in the peculiar construction and novel combination of parts that will be more fully set forth hereinafter, and particularly pointed out in the claims.

15 In the accompanying drawings, Figure 1 is an elevation of a breech-loading gun embodying our improvements, showing the same arranged in the firing position. Fig. 2 is a similar view of the same with a portion of the 20 lock-case removed, so as to disclose the interior mechanism. Fig. 3 is a top plan view of our improved breech-loading gun. Fig. 4 is a vertical longitudinal sectional view of the same, taken on the line $x-x$ of Fig. 3, and 25 showing the parts of the gun in position for extracting the cartridge-shell. Fig. 5 is a detailed perspective view of the extracting-arm and the pivot therefor. Fig. 6 is a similar view of the breech-block. Fig. 7 is a detail 30 view of the tang or link.

A represents the lock-case, which is made of a single piece of metal, has its lower side open, and is provided at its rear upper corner with a rearward-extending tang or arm, B, 35 which is adapted to fit in a recess, C, in the upper side of the stock D. The front upper corner of the case is provided with a longitudinal-threaded opening, E, in which is screwed the breech of the barrel F.

40 G represents a vertical opening, which is made through the lock-case immediately in rear of the breech of the barrel, and H represents a vertical opening, which is made in the upper side of the lock-case in rear of and communicating with the opening G. The latter extends entirely through the lock-case, and the opening H communicates with the hollow interior or chamber I of the lock-case. Said chamber I and vertical opening G are separated by a vertical partition, K, which is 45 formed of the same piece with the lock-case.

In the lower front corner of the opening G is formed a recess, L.

M represents a bolt or pin, which passes transversely through the lock-case and 55 through the front side of the opening G, and is arranged at a suitable distance below the bore of the barrel. The said pin or bolt is in contact with the front side of opening G. Pivoted on the said pin or bolt, near one end 60 thereof, is an extractor-arm, N, which is normally arranged in a vertical recess, O, and has its upper end inclined inwardly toward the bore of the barrel. The usual annular groove, P, is made in the breech of the barrel 65 for the reception of the base-rim of the cartridge, and a portion of this groove is formed in the upper end of the extractor-arm. From the rear side of the extractor-arm, at the lower end thereof, projects a cam, R, and 70 arranged at substantially right angle to the cam is a depending detent point, S, which is adapted to engage the front wall of the opening G when the extractor-arm has been inclined rearward to the extent necessary to 75 cause the same to withdraw the cartridge-shells from the breech of the barrel.

T represents the breech-block, which is adapted to fit in the opening G, and has its front and rear sides parallel, and its upper 80 end curved, as shown. In the front side of the breech-block, near the lower end thereof, is formed a transverse recess, U, the inner side of which is sigmoidal in shape. On one side of the breech-block, at the front end 85 thereof, is a recess, V, which is vertical, communicates with the recess U, and has its upper and lower sides curved and inclined downward and forward. The rearward-projecting cam and the downward-extending point of 90 the extractor-arm are contained in the recess V when the breech-block is raised, so as to close the breech of the barrel and bear against the base of the cartridge. At the rear lower corner of the breech-block are formed a pair of 95 depending-ears, W.

X represents a firing-pin of the usual construction, which is arranged in the upper portion of the breech-block.

Y represents the guard-lever, which is of 100 the usual shape, and is provided at its front end with an arm, Z, which enters the recess

L of the lock-case, and is pivoted on a pin or bolt, A'. On the upper side of the guard-lever, near the front end thereof, are formed a pair of ears, B'.

5 C' represents a link, which has its upper end pivoted between the ears W of the breech-block by means of a pin, D', and has its lower end pivoted between the ears D' of the guard-lever by means of a pin, E', and thereby the 10 breech-block is connected to and adapted to be operated by the guard-lever.

15 F' represents the hammer-block, which is arranged in the recess I of the lock-case, and has a rearward-extending arm, which is provided at its rear end with an elongated transverse opening, H', and is adapted to fit between the ears C of the tang B. A pin, I', passes through transverse openings in the 20 said ears, and through the opening H', and thereby pivots the hammer-block to the tang and enables the said hammer-block to swing up and down in the lock-case and to play longitudinally to a slight extent on the pivot. The lower front corner of the hammer-block 25 is provided with a forward-extending arm, K', which is adapted to be engaged by a shoulder, L', near the front end of the guard-lever. The hammer-block is formed of two parts, M' and N', which are secured together 30 by a pair of screws, O', and have an opening, P', formed between their opposing sides in the upper portion of the block, in which is fitted the lower end of the hammer R'. Said hammer is of the usual construction, and has 35 its lower end pivoted on a pin.

T' represents a detent, which is pivoted in the hammer-block and has one end curved upward and adapted to engage the notches in the lower end of the hammer, so as to secure the latter at half or full cock, as in the 40 usual manner. The rear end of the detent T' rests upon a rearward-extending arm, U', which is formed at the upper end of the trigger V'. Said trigger is pivoted on a pin, W', 45 that passes transversely through the parts of the hammer-block, and the lower end of the trigger projects downward from the hammer-block, as shown.

X' represents a spring, which bears against 50 the upper side of the detent T' at a suitable distance in rear of its pivot, the function of the said spring being to keep said detent in engagement with one of the notches of the hammer.

55 Y' represents the main hammer-spring, which has its rear end secured in a notch near the rear end of the arm G', and has its front end connected to a rearward-extending arm, Z', at the lower end of the hammer by 60 means of a T-headed link, A², the upper end of which is loosely connected to the free end of the spring Y'.

B² represents a flat spring, which is arranged at a suitable distance under the spring 65 Y', has its rear end secured in a notch on the upper side of arm G', and has its front

end bearing downward on the arm Z' of the hammer, the function of the said spring being to cause the hammer to rebound immediately after discharging the cartridge. The upper 70 portion of the hammer is passed through the portion H in the lock-case.

C² represents a tang or link, which has its front end provided on opposite sides with shoulders D², which engage notches or grooves 75 E², formed in the interior of the lock case, at the lower inner corner thereof. The rear portion of the said tang is fitted in a longitudinal groove, F², which is made in the lower side of the stock. Screws G² extend transversely through the sides of the lock-case at the lower rear corner thereof, and engage the 80 front end of the tang C², and vertical bolts H² pass through the rear end of said tang and engage the stock. The tang C² and tang B 85 serve to secure the lock-case rigidly to the stock, as will be readily understood.

The operation of our invention is as follows: When the gun is in its firing position, the guard-lever is turned upward against the 90 lower side of the stock, so as to cause the link C' to force the breech-block upward in the opening G, so as to close the breech of the barrel and bear against the base of the cartridge, and the shoulder L' of the guard-lever 95 engages the arm K' of the hammer-block and thereby raises the latter. The hammer is cocked in the usual manner, and the piece is discharged by pulling the trigger, so as to cause the hammer to descend and 100 strike the firing-pin. The guard-lever is then swung downward, so as to cause the link C' to draw downward on the breech-block. The first portion of the downward movement of the latter is in a vertical direction until 105 the shoulder at the upper end of the recess U in the front side of the breech-block comes in engagement with the pin or bolt M, on which the extractor-arm is pivoted. Said pin or bolt then acts as a pivot for the breech-block, and 110 as the guard-lever continues to swing downward the link C' draws forward on the rear corner of the breech-block and consequently swings or partly rotates the breech-block, so as to cause the upper end thereof to swing 115 rearward and downward in the opening G and from the breech of the barrel. The first or vertical portion of the descent of the breech-block is effected independently of the extractor-arm, because the vertical portion of 120 the recess V enables the breech-block to clear the cam of the extractor-arm; but when the said breech-block reaches the lower limit of its vertical movement the shoulder at the upper end of its recess V engages the upper rear 125 end of the said cam, and consequently as the breech-block moves rearward in its circular path it exerts such great pressure upon the cam-arm of the extractor as to cause the latter to swing rearward on its pivot, and being 130 in engagement with the rim at the base of the cartridge-shell the said extractor-arm

causes the cartridge-shell to be withdrawn from the breech of the barrel, as will be very readily understood.

The ears B' on the upper side of the guard-lever engage the arm K' at the front end of the hammer-block as the guard-lever moves downward, and consequently cause the front end of the hammer-block to be lowered, so as to partly withdraw the hammer into the lock-case, where it will be entirely out of the way, and hence the person using the gun has free access to the breech of the barrel and can readily insert another cartridge therein.

It sometimes happens after a gun has been repeatedly discharged that the cartridge binds or sticks in the breech before it is driven home therein, and in the breech-loading guns now in common use this is a serious objection, for the reason that the projecting rear end of the cartridge becomes engaged by the breech-block and the mechanism of the gun is prevented from being operated. Our improved breech-loading gun hereinbefore described is not open to this objection, because our breech-block, after being partly lowered, completes its movement by swinging rearwardly from the breech of the barrel. In the event that a cartridge should stick while being inserted in the breech of our improved gun, the operator raises the guard-lever and at the initial movement thereof the link C', by pressing rearward on the rear lower corner of the breech-block, swings the upper end of the breech-block forward, the pin or bolt M, forming the fulcrum of the breech-block, and rearward play of the latter being prevented by the transverse partition K, and consequently the leverage exerted upon the breech-block is so great that the front upper end of the same engages the base of the cartridge and forces it home in the breech of the barrel. As the guard-lever continues to ascend, the rear side of the breech-block is caused to bear squarely against the vertical partition K, and consequently the breech-block is guided in a vertical direction and caused to move upward in contact with and rear of the base of the cartridge. As the guard-lever continues to swing upward, the lower end of the link C' is gradually raised, and by the time the rear end of the guard-lever is in contact with the lower side of the stock said link has passed the dead-center—that is to say, its front end is slightly higher than its rear end—and the link is thereby caused to retain the guard-lever in its elevated position, so as to lock the same and the mechanism in the lock-case.

Having thus described our invention, we claim—

1. The combination, in a breech-loading gun, of the case having the vertical guideway G at the rear of the breech of the barrel, the breech-block having its front and rear sides parallel and adapted to move in the vertical way G, the upper end of said block being rounded and the front side thereof being pro-

vided with the vertical recess, the pin or bolt M, secured in the lock-case and engaging said recess, the guard-lever pivoted to the lock-case, and the link connecting the same to the breech-block, for the purpose set forth, substantially as described. 70

2. The combination, in a breech-loading gun, of the lock-case, the vertical guideway G 75 in rear of the breech of the barrel, the pin or bolt M, arranged transversely in the front side of the guideway, the breech-block fitted in the guideway G and having its front and rear sides parallel, said breech-block having its upper side rounded, provided in its front side with the vertical transverse notch U, engaging pin or bolt M, and having the vertical recess V on one side communicating with said notch, the extractor-arm pivoted on the pin 80 or bolt M and having the rearward-extending cam at its lower end working in recess V, the guard-lever pivoted to the lock-case, and the link connecting the guard-lever to the breech-block, substantially as described. 85

3. The combination of the lock-case having the vertical guideway G, the vertically-reciprocating breech-block arranged in the said guideway, provided with the ears D', and having the slot or recess U in its front face, 95 the pivotal pin M, seated in the lock-case and engaging the slot or recess U, the guard-lever pivoted to the lock-case and having the ears B', and the link C', having one end pivoted in said ears B' and the other end pivoted in the ears D', substantially as described. 9c

4. The combination, in a breech-loading fire-arm, of the lock-case, the breech-block guided therein, the guard-lever pivoted to the lock-case and having the shoulder L', the link connecting the said lever to the breech-block, and the pivoted swinging hammer-block carrying the hammer and trigger and having the arm K', engaging the shoulder L' 105 of the guard-lever, substantially as described. 110

5. The combination, in a breech-loading gun, of the lock-case, the movable breech-block guided therein, the pivoted guard-lever connected to the breech-block and having the shoulder L', and the pivoted hammer-block carrying the hammer and trigger and trigger-spring and having the arm K', adapted to engage the shoulder L' of the guard-lever, for the purpose set forth, substantially as described. 115 120

6. The combination, in a breech-loading fire-arm, of the lock-case having the vertical guideway G, the recess I, the opening H, and the partition K between the recess and the guideway, the pin or bolt M, arranged transversely in the front side of the guideway, the extractor-arm pivoted on said pin or bolt and having the cam on its lower end, the breech-block fitted in the guideway having its upper side rounded, provided on its front side with the vertical recess U, engaging the pin or bolt M, and having the recess V on one side engaging a cam of the extractor-arm, the 125 130

guard-lever having its front end pivoted to the lock-case and provided with the shoulder L', the link connecting said rod or lever to the breech-block, for the purpose set forth, the
5 hammer-block arranged in the recess I and having its rear end pivoted, said hammer-block having its front end provided with the arm K', engaging the shoulder L', and the hammer, trigger, and spring secured to and
10 carried by the hammer-block, the hammer being adapted to move upward and downward in the opening II, substantially as described.
7. In a fire-arm, the combination of the
15 lock-case, the vertically-movable breech-

block guided therein and having the transverse vertical recess, the upper end of the breech-block being rounded, the pivotal pin or bolt in the recess, and the guard-lever and connections between the same and the breech- 20 block, substantially as described.

In testimony that we claim the foregoing as our own we have hereto affixed our signatures in presence of two witnesses.

JOHN H. REDFIELD.
SAMUEL H. REDFIELD.
